DESIGN FOR A JEWELRY COMPONENT

Charles du B. Arcularius, New Canaan, Conn.

Application January 2, 1947, Serial No. 135,900

Term of patent 14 years

(Cl. D45—1)

To all whom it may concern:

Be it known that I, Charles du B. Arcularius, a citizen of the United States and a resident of New Canaan, county of Fairfield, and State of Connecticut, have invented a new, original, and ornamental Design for a Jewelry Component, of which the following is a specification, reference being had to the accompanying drawing, forming a part thereof, and wherein

Figure 1 is a top plan view of a jewelry component, embodying my new design; and

Figure 2 is a side elevational view thereof.

I claim:

The ornamental design for a jewelry component, substantially as shown.

CHARLES du B. ARCULARIUS.
